UNITED STATES PATENT OFFICE.

EDWIN E. JONES, OF CLEVELAND, OKLAHOMA TERRITORY.

FURNACE.

No. 829,217.

Specification of Letters Patent.

Patented Aug. 21, 1906.

Application filed September 19, 1905. Serial No. 279,070.

To all whom it may concern.

Be it known that I, EDWIN E. JONES, a citizen of the United States, and a resident of Cleveland, in the county of Pawnee and Territory of Oklahoma, have invented a new and Improved Furnace, of which the following is a full, clear, and exact description.

The essential object of my invention is to provide a furnace by means of which the gases of combustion will be effectually consumed, and in this manner the best possible heating effect obtained. In securing this end I provide a flue passing from or communicating with the fire-box, which flue is preferably though not necessarily a downtake-flue and which has a certain peculiar formation, causing the heavier and lighter bodies of the gases of combustion to take movement along crossing or interfering lines, thus bringing about repeated intimate association between the colder and hotter gases and causing the combustible in the colder gases which would otherwise escape through the stack of the furnace to be ignited and consumed by the heat of the hotter gases. In this manner as the gases pass from the fire-box all of the combustible in the gases is burned and the best thermal efficiency is attained.

The invention involves various other features of major or minor importance, all of which will be fully set forth hereinafter, and particularly pointed out in the claims.

Reference is had to the accompanying drawings, which illustrate, as an example, one manner of embodying my invention in a stationary boiler-furnace, in which drawings—

Figure 1 is a sectional view of the invention on the irregular line 1 1 of Fig. 2. Fig. 2 is a sectional plan on the line 2 2 of Fig. 1; 40 and Figs. 3, 4, 5, and 6 are cross-sections of the flue, respectively, at the points marked 3 3, 4 4, 5 5, and 6 6 in Fig. 2.

According to the arrangement shown in Fig. 1, 10 indicates the shell of the boiler, 11 the fire-box, and 12 the downtake-flue passing from the fire-box through the boiler-shell to the smoke-box 14. From the smoke-box 14 the return-flues 15 carry the gases into the stack or chimney 16, which passes from the shell 10 over the fire-box 11. As shown in Fig. 2, the flue 12 is curved laterally, giving the flue an undulatory or sinuous form. The flue has the shape of a double compound curve. At the point 12^a (see Figs. 2 and 3) 55 the flue is depended, and at the correspond-

ingly opposite point 12^b the flue is relatively shallow. At the point 12^c the flue is deepened and made relatively shallow at the point 12^d. (See Figs. 2 and 4.) At the point 12^e the flue is deepened, and at the point 12^f it is relatively shallow. (See Figs. 2 and 5.) At the point 12^g the flue terminates in the smoke-box 14 with approximately a uniform depth. (See Figs. 2 and 6.)

Referring to Figs. 2 to 6 of the drawings, it will be seen that the elevated portions 12^a and 12^c and 12^e occur at opposite sides of the flue, while the shallow or depressed portions 12^b and 12^d and 12^f also occur at opposite sides and are arranged oppositely with respect to the deep or elevated portions of the flue. The result of this construction is that as the gases pass from the fire-box the hottest gases will enter the flue at the elevated portion 12^a, and as these gases approach the depressed portions 12^d and 12^f said gases will cross over to the opposite side of the flue into the elevated portions 12^c and 12^e. At the same time the colder gases will enter the flue and take a position at the depressed or shallow part 12^b of the flue and in traversing the flue will encounter the hot gases crossing from one point to the other, the colder gases being forced across the flue to the depressed portion 12^d and 12^f. It will be seen, therefore, that the peculiar construction which I employ separates the hotter and colder gases into two distinct currents which are forced to cross or intersect each other, thus bringing about a thorough intermingling of the hot and cold gases and causing the combustible in the colder portions of the gas to be ignited and burn completely before the gases pass from the furnace. As the gases cross each other and mingle in the part of the flue indicated by the characters 12^c, 12^d, 12^e, and 12^f the mingled and burning gases pass on in a body and are discharged from the end 12^g. The sinuous or undulatory form of the side walls of the flue also greatly enhances the above-described action. It is pointed out that the flue may be given any desired number of turns, and it is also pointed out that the elevated and depressed portions in the flue may be multiplied at will, causing the hotter and colder gases to separate after their first intersection and again to intersect or mingle, so as to repeat the operation any number of times desired.

Having thus described the preferred form

of my invention, what I claim as new, and desire to secure by Letters Patent, is—

1. A furnace having means for causing the hotter and colder gases of combustion to move along intersecting or crossing courses, whereby to bring about an effectual mingling of said gases, for the purpose specified.

2. A furnace having a flue for the gases of combustion, said flue having at two points along its length relatively high and low portions located opposite each other, and the high and low portions at one point being respectively at the sides of the flue opposite the sides having the high and low portions at the other point, whereby to cause the hotter and colder gases of combustion to move along intersecting courses and bring about effectual commingling of said gases.

3. A furnace having a flue for the gases of combustion, said flue having an essentially flat bottom, and having at different points along its length relatively high and low top walls located opposite each other, and the high and low top walls at one point being respectively at the sides of the flue opposite the sides having the high and low top walls at the other point, whereby to cause the hotter and colder gases of combustion to move along intersecting courses and bring about effectual commingling of said gases.

4. A furnace having means for causing the hotter and colder gases of combustion to move along intersecting or crossing non-vertical courses, whereby to bring about an effectual mingling of said gases, for the purpose specified.

5. A furnace having a flue for the gases of combustion, said flue having an essentially flat bottom and curving in essentially the plane of said bottom, and the flue having at different points along its length relatively

high and low walls located opposite each other, the high and low top walls at one point being relatively at the sides of the flue opposite the sides having the high and low top walls at the other point, whereby to cause the hotter and colder gases of combustion to move along intersecting courses and bring about effectual mingling of the gases.

6. A furnace having a non-vertical flue for the gases of combustion, said flue having an essentially flat bottom and curving in essentially the plane of said bottom, and the flue having at different points along its length relatively high and low walls located opposite each other, the high and low top walls at one point being relatively at the sides of the flue opposite the sides having the high and low top walls at the other point, whereby to cause the hotter and colder gases of combustion to move along intersecting courses and bring about effectual mingling of the gases.

7. A furnace having means for causing the hotter and colder gases of combustion each to move along curving non-vertical lines or courses, which lines or courses intersect each other to bring about effectual mingling of said gases, for the purpose specified.

8. A furnace having means for causing the hotter and colder gases of combustion each to move along curving lines or courses, said lines or courses intersecting each other to bring about an effectual mingling of said gases, for the purpose specified.

In testimony whereof I have signed my name to this specification in the presence of two subscribing witnesses.

EDWIN E. JONES.
